SPRING CUSHION STRUCTURE

Abraham Krakauer, Brooklyn, N. Y., assignor to
 Kay Manufacturing Corporation, Brooklyn,
 N. Y., a corporation of New York

Application January 17, 1936, Serial No. 59,485

7 Claims. (Cl. 5—272)

This invention relates to spring structures for cushions, mattresses, bed bottoms and the like and particularly, to the type in which a series of similar upstanding coil springs are arranged in 5 parallel rows and secured together.

My invention contemplates the provision of suitably shaped and diametrically opposed looped locking portions in the end coils of the various springs by means of which adjacent springs may 10 be interlocked with each other and/or with a frame wire or bracing wire in hinged relation 15 by means of indented wires passing through said locking portions.

My invention further contemplates the provision 20 of securing means for the springs, which means is arranged at all times in such relation to the end coils of the springs that said means cannot injure the covering layers of filling material customarily used in mattresses, cushions 25 and pillows of the type to which this invention is applicable.

My invention further contemplates the provision 30 of securing means for the springs which are so shaped that said means are free of projections which would tend to wear through the filling material in the course of time.

My invention further contemplates the provision 35 of a spring structure designed to be economically and quickly made and assembled and securely held together against relative movement 40 in any direction except a relative hinging movement by means of a minimum quantity of comparatively thin wires.

The various objects of my invention will be 45 clear from the description which follows, and from the drawings, in which,

Fig. 1 is a fragmentary top plan view of a spring structure embodying my invention, it being understood that the remaining parts of the structure 50 are constructed similarly to those parts shown to form the complete cushion or mattress.

Fig. 2 is a vertical section of one of the coil springs and of the connecting wires.

Fig. 3 is a fragmentary perspective view of the 55 interlocked end coils of adjacent springs and the securing wire therefor.

Fig. 4 is a fragmentary top plan view of a somewhat modified form of the spring structure, 60 wherein the springs are anchored at two diametrically opposed points only.

Fig. 5 is a similar view of another modified 65 form of the structure wherein the springs are each anchored at four points.

Fig. 6 is a view similar to Fig. 3 but wherein

a pair of indents are made in the securing wire outside of the locking portions of the end coils.

In the practical embodiment of my invention which I have illustrated by way of example in Fig. 1, the coil springs 10, 11, 12, 13 and possibly 5 other similar springs not shown are arranged to form an edge row. Similarly, the springs 14, 15, 16 and 17 form part of an intermediate row which may be adjacent the center of the cushion of which said row of springs forms a part, or if the 10 cushion or mattress is so wide that the springs 10 and 14 do not reach to the center of the cushion, said row of springs 14, 15, 16 and 17 may constitute an intermediate row similar to the next 15 succeeding row which next row comprises in part, the springs 18, 19 and 20. The number of intermediate rows and the number of springs in each row may obviously be greatly varied in accordance with the size of the article in which the structure is to be used. It will be understood, 20 however, that the peripheral or edge row of springs on the right edge of the spring structure, as viewed in Fig. 1, is similar to the first described edge row consisting of the springs 10, 11, 12, 13, and hence the right hand edge row need 25 not be shown nor further described.

All of the springs, however, are preferably made substantially identical in size and shape and therefore, a description of one of the springs will suffice for all. The end coils 21 and 22 of 30 the spring are each provided with one or more pairs of diametrically opposed and suitably shaped parts providing integral locking members by means of which the end coil may be secured to the end coil of one or more adjacent springs, 35 or to the frame wire 23, or to auxiliary bracing wires, where such bracing wires are found to be desirable.

In those cases where it is desired to anchor the end coils of each spring at two points only, a single pair 8, 9 of locking members is provided in 40 each of the end coils (Fig. 4). Where, however, the end coils are to be anchored at three points, as indicated in Fig. 1, an additional locking member may be bent integrally from the end coil substantially midway between the pair of locking members 8 and 9.

The additional locking member may be of the same size as either of the locking members of the pair since said additional member is locked to 50 either the frame wire 23 or to a transverse bracing or auxiliary wire 50. However, to avoid the necessity of arranging the springs in any particular predetermined position with respect to the locking members and for convenience in manu- 55

facture, a complete additional pair of locking members may be provided on a diameter of the end coil at right angles to the diameter passing through the centers of the pair of locking members 8 and 9. I have therefore shown this form of end coil in Fig. 1 wherein two pairs of locking members are provided even though the spring is shown as anchored at three points only of its end coil.

10 In Fig. 5, I have shown each end coil of the spring anchored at four points whereby both pairs of locking members are utilized in the formation of the spring structure.

15 It will be understood that the locking members of a pair are similar in construction and formation though differing in width. Each of the locking members comprises a pair of parallel spaced loops each closed at one end and open at the other, the closed end of the loop being positioned 20 at a point outwardly beyond the remainder of the end coil from which it is integrally bent. Each of said loops is arranged in a plane parallel to the axis of the spring, which plane is customarily vertical. The loops are integrally 25 joined to each other by a continuation of the corresponding parts of the open ends thereof, the remainder of the open end of the loop being integrally joined and bent directly from the end coil.

30 As shown in Fig. 3, there is thus provided a bent portion in the end coil 21 of the spring 10, which bent portion constitutes a locking member and comprises a pair of spaced vertical loops 25, 26, which loops are open as at 27 to permit the 35 locking member to be hingedly connected to the locking wire 24 and which loops are joined integrally by a U-shaped portion 28. The loops 25 and 26 and the U-shaped connecting portion 28 constitutes the narrower locking member 9.

40 Similarly, the locking member 8 of the end coil 21' of the spring 11 comprises a pair of loops 30, 31 open respectively at the respective ends 32, 33 thereof and joined by the integral U-shaped portion 34, the loops 30 and 31 being 45 spaced apart sufficiently to receive the loops 25, 26 of the locking member 9 therebetween.

The U-shaped portions 28 and 34 are arranged below the end coils 21 and 21' respectively. Similarly, the corresponding U-shaped parts of the 50 locking members in the end coil 22 are arranged above the plane of said end coil 22 so that in either case, the U-shaped parts of the locking members are in vertical spaced relation to the respective end coils from which they are bent and hence the upper surface of the spring structure is free of projections which might engage the filling material.

55 It will also be seen that when the locking members are interlocked, a space as 35 is provided between the U-shaped connecting parts 28 and 34 for the reception of the indent 36 of the locking wire 24.

In the preferred mode of assembling the 60 springs, the loops 25, 26, 30 and 31 of the locking members 9 and 8 are preferably positioned with the openings thereof in alignment and thereby arranged for the reception of the preferably straight locking wire 24. After said wire has been inserted through the loops, it is indented as at 36 to protrude through the space 35 in a direction away from the adjacent end coils of the springs which it connects. It will be understood, however, if desired, that the indents 36 may be preformed at the proper spaced intervals in the

wire 24 before its assembly with the locking members 8 and 9.

In this case, the parts are assembled by passing the end coils of the springs transversely across the wire 24 to arrange the indent 36 thereof in the space 35 of the locking member 8 while at the same time passing the locking member 8 in the opposite direction transversely across the wire 24 to arrange the loops 25 and 31 outside of the loops 25 and 26 respectively, the indent 36 being also arranged at the same time in the space 35 inside of the U-shaped member 34. The wire thus passes through the open ends 27 of the loops 25 and 26 and also passes through the open ends 32 and 33 of the loops 30 and 31. It is preferable when thus assembling the locking members and the wire 24, to arrange the end coils 21 and 21' of the respective springs in relatively inclined planes to facilitate the assembling operation.

Whether or not the indents 36 are made in the wire 24 before or after the wire has been assembled with its locking members, the open ends 32 and 33 of the respective loops 30 and 31 are preferably partly or entirely closed by bending the U-shaped member 34 toward the adjacent 25 end coil 21' and thereby to carry said U-shaped portion into contact with or close to the closed ends of the loops 25 and 26.

It will be seen that the wire 24 locks the end coils of the springs 10 and 11 hingedly together 30 against movement in any direction except a relative swinging movement about the wire 24. Since the indent 36 is preferably long enough to extend between the loops 25 and 26, the end coil of the spring 10 cannot move in a direction longitudinal of the wire 24. Nor can said end coils move relatively in a transverse or vertical direction, being prevented from doing so by the engagement of the loops 25, 26, 30 and 31 with the wire 24, and the engagement of the U-shaped 35 part 34 with the loops 25 and 26. Said wire 24 cannot twist to any material extent sufficient to unlock the parts since a twisting movement causes the indent 36 thereof to engage either of the U-shaped part 28 or 34. It will thus be seen 40 that the end coils of the springs are locked to each other and to the wire 24 and are prevented from any relative movement except a hinging or rotary movement about the wire 24, and that the interlocked springs and wire are thereby compelled to move bodily as a unit under the pressure 45 put upon the structure.

The wire 24 is preferably secured at its ends to the frame wire 23 as by means of the coil or twist 37. It will be understood that the frame 50 wire 23 extends completely around the spring structure and that while only part of said wire and said structure is shown in Fig. 1, the remainder of said structure is similar to that shown. Where, as in Fig. 1, an additional locking member as 38 is provided midway between the members 8 and 9 of the end coil 21, said member 38 is secured to the frame wire 23 by the passage 55 of said frame wire through the loops 30 and 31 thereof, a downward indentation as 39 being 60 made in the frame wire between said loops to lock the spring against longitudinal movement 65 relatively to the frame wire.

The end coil of the corner spring 10 may be additionally secured to the side 40 of the frame 70 wire by means of a locking member 8 thereof and an indent 41 in the frame wire.

The corner spring 10 is thus secured to one side of the frame wire 23 and also to the other side 40 of said frame wire, the end coils being fur- 75

ther secured to the corresponding end coils of the adjacent spring 11 to provide a three point anchorage for the upper and lower end coils.

Similarly, in any of the intermediate rows, if a three point anchorage is desired, the springs are secured to each other and either to the frame wire or the optional auxiliary or bracing wire 58 secured at its ends as at 51 to the side 48 of the frame wire 23. For example, the end 10 coil of the spring 14 is secured to the frame wire as by means of the indent 43. Said end coil is also secured to the auxiliary wire 50 by means of the additional locking member 42 and is further secured to the end coil of the adjacent spring 15 by the locking members hereinbefore described. Similarly, the end coils of the spring 15 are secured to the end coils of the adjacent springs 14 and 16 as well as to the auxiliary wire 50.

Where, however, the use of less wire is desirable, a two point anchorage for each of the intermediate rows of springs may be provided and the edge row may be secured to the frame wire by means of ordinary sheet metal clips bent 25 around the spring and the frame wire in a manner well known in the art and hence which need not be shown nor described. The two point anchorage for the springs or intermediate rows is shown in Fig. 4 wherein the bracing wires 50 are omitted and a single pair of locking members 8 and 9 is provided in each of the end coils of each spring.

Referring to the edge spring 52, the locking member 8 thereof is secured to the frame wire 53 in the same manner as hereinbefore described in connection with the spring 14. The locking member 9 is joined to the corresponding member 8 of the adjacent spring 54 by the locking wire 55 as hereinbefore described in connection 40 with the wire 24.

In some cases, it may be desirable to anchor the springs at four points. As shown in Fig. 5, the spring 60 is provided with the pair of locking members 61 and 62 and also with the additional pair of locking members 63 and 64. It thereby becomes possible to interlock the spring 60 with the adjacent spring 65 by means of the locking member 61, the locking wire 66 and the corresponding narrower locking member of the spring 65. Similarly, the spring 60 may be locked to the adjacent spring 67 by means of the locking wire 68. If desired, the locking wires 66 and 68 may be made only of sufficient length to project a comparatively small extent beyond the loops of the locking members though in the structure shown in Figs. 1 and 4, it is preferable though not essential that the corresponding locking wires 24 and 55 extend completely across the structure and be tied to the frame wire.

Referring again to Fig. 5, the short locking wires 69 and 70 hingedly connect the locking members 63 and 64 respectively, to the corresponding locking members of the respective adjacent springs 71 and 72. Said comparatively short wires 69 and 70 are each provided with an indent as 73 similar to the indent 36 of the wire 24, which indent may be preformed before the wire is inserted through the loops of the locking members or which may be made later after the assembly, as may be found convenient.

As shown in Fig. 6, for the indent 36 entering the space 35 may be substituted a pair of indents 74 and 75 made in the locking wire 76 and arranged beyond the loops 38 and 31, respectively.

Said indents function in the same manner as the indent 36 preventing longitudinal movement of the end coils relatively to the locking wire 76, whether said wire be long or short.

A spring structure is therefore provided in which there are no projecting parts on the upper or lower surface of the structure which would tend to wear through or to injure the comparatively soft filling material which is arranged on the upper and lower surfaces of the structure. 10 A structure is further provided whereby the springs are hinged to each other and cannot otherwise move relatively to each other under pressure.

It will be seen that by means of the structure above described, I have provided a simple and economical interlocking arrangement of the springs of a spring structure, the parts of which are quickly and easily assembled, and which structure is well designed to meet the severe 20 requirements of practical use.

While I have shown and described a certain specific embodiment of my invention, I do not wish to be understood as limiting myself thereto since I desire to claim my invention as broadly 25 as may be permitted by the state of the prior art and the scope of the appended claims.

I claim:

1. In a spring structure, a first coil spring having an upper end coil and a lower end coil, each 30 of said end coils being provided with an integral locking portion bent from the material of the end coil at a point in spaced relation to the extremity of said coil, said locking portion comprising a pair of loops arranged in substantially 35 parallel relation and spaced a predetermined distance apart, the outer end of each of said loops remote from the end coil being closed and the other ends of said loops being open and joined by a U-shaped member arranged in lateral spaced 40 relation to the remainder of the end coil, a second coil spring having end coils, a locking member bent integrally from the material of each of the end coils and adapted to engage and to be locked to the locking portion of said first spring, 45 each of said locking members comprising a pair of parallel spaced closed loops extending outwardly from the end coil and being spaced apart a distance greater than that between the loops of said first spring, said closed loops each having 50 an integral bend at one end thereof and being joined at the other ends thereof by a connecting portion integral therewith and arranged inwardly of the end coil, said closed loops being respectively arranged in outwardly adjacent relation to 55 the respective open loops, and extending transversely from said springs in opposite directions, a wire passing through said closed and open loops, and an indented portion in the wire arranged in a plane at substantially right angles 60 to the planes of the loops and adjacent said loops, said wire being prevented from moving transversely in one direction by the closed ends of the loops of said first spring and from moving in the other direction by the integral bends of 65 the closed loops.

2. In a spring structure, a pair of coil springs, each having an end coil, a pair of locking members one wider than the other bent integrally from the end coil of each of the springs, the 70 wider locking member of one spring embracing the narrower locking member of the other spring, each of said narrower locking members comprising a pair of spaced loops arranged in respective parallel vertical planes, each of said loops 75

- being open at one of its ends, and being connected at its open end by a transverse member to the open end of the other loop, the wider locking members having a pair of spaced vertical loops each arranged adjacent and parallel to a loop of the narrower locking member, a straight wire passing through the four loops of said locking members, and a vertical indent in the wire between the loops of the narrower locking member, said indent being of sufficient depth to prevent longitudinal movement of said wire relatively to said loops and to prevent material rotation of said wire in said loops.
3. In a spring structure, means for locking a pair of coil springs together comprising a locking member in and integral with the end coil of one of the springs, a narrower locking member in and integral with the end coil of the other spring and arranged within the first-mentioned locking member, each of said locking members comprising a pair of spaced substantially parallel loops bent from the material of the end coil, and a wire passing through the four loops of the locking members and provided with a pair of depressed shoulders each adjacent one of the loops and arranged in a plane substantially parallel to the axis of the spring, all of said loops being in planes also substantially parallel to said axis.
4. In a spring structure, a series of coil springs arranged in rows, and means for locking adjacent springs of a row together to anchor the end coils of each spring at a plurality of spaced points, said means comprising a plurality of locking members in each of the end coils of each spring, one of the locking members being wider than another, each of said locking members comprising a pair of spaced outwardly extending loops and a bent portion integral with and connecting the loops and arranged inwardly of the adjacent part of the end coil, the spaces enclosed by the loops of the wider locking member of one spring being arranged in alignment with and outside of the spaces enclosed by the loops of the narrower locking member of the adjacent spring, and means for hingedly connecting said loops together and preventing relative longitudinal movement thereof.
5. In a spring structure, a series of coil springs, a locking member in each of the end coils of each spring, the locking members of adjacent springs overlapping each other and each comprising a pair of spaced loops integrally connected to each other, one of the overlapping locking members being wider than the other, a

frame wire around the periphery of the structure, locking wires each extending completely across the structure and through the four loops of each pair of overlapping locking members, the ends of each of said locking wires being secured to the frame wire, indents in the locking wires adjacent the loops, and means for connecting the end coils of the outermost springs to said frame wire.

6. In a spring structure, a series of coil springs arranged in rows, a frame wire secured to the springs of the outer rows, a pair of loops extending outwardly from each of the end coils of adjacent springs and arranged in planes parallel to the axis of the springs, at least one of the loops of one pair being arranged between the loops of the other pair, and transverse locking wires each passing through both of the pairs of the loops of adjacent springs and secured at both ends to the frame wire.

7. In a spring structure, a series of rows of coil springs, the end coils of each of said springs each having a pair of circumferentially spaced locking members integrally bent therefrom, one of said locking members being wider than the other, said one locking member comprising a pair of parallel, outwardly projecting, spaced, substantially closed, bent loops providing a pair of spaced vertical eyes, said loops being integrally joined by a member arranged inwardly of the adjacent part of the end coil, said other locking member comprising a pair of parallel outwardly projecting bent loops providing a pair of vertical eyes spaced apart a distance less than the distance between the eyes of said one locking member, a member integrally joining the loops of said other locking member and arranged inwardly of the adjacent part of the end coil, said one locking member of each of the springs in a row receiving said other locking member of the adjacent spring in the row to align the eyes of said locking members, and a wire passing through all of the eyes of the interengaging loops of the springs in adjacent rows, the bends of the loops in said one locking member preventing transverse movement of the wire in one direction and the bends of the loops in said other locking member preventing transverse movement of the wire in the other direction, said wire having a vertical indent therein adjacent the loops and preventing relative movement of the locking members and the wire longitudinally of the wire.

ABRAHAM KRAKAUER.
